Primary Examiner — Janice Seeger(74) *Attorney, Agent, or Firm* — Maschoff Brennan(57) **CLAIM**

The ornamental design for an outer edge of a table top, as shown and described.

DESCRIPTION

FIG. 1 is an upper perspective view of an outer edge of a table top; and,

FIG. 2 is a cross sectional side view of the outer edge shown in FIG. 1 along lines 2-2.

The broken lines shown in the figures are for illustrative purposes only and form no part of the claimed design.
